(57) **CLAIM**

The ornamental design for a set of vehicle steering wheel control switches as shown and described.

DESCRIPTION

FIG. 1 is a top, front and right side perspective view of a set of vehicle steering wheel control switches, showing a first embodiment of our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a bottom plan view thereof.

FIG. 7 is a top, front and right side perspective view of a set of vehicle steering wheel control switches, showing a second embodiment of our new design;

FIG. 8 is a front elevational view thereof;

FIG. 9 is a left side elevational view thereof;

FIG. 10 is a right side elevational view thereof;

FIG. 11 is a top plan view thereof; and,

FIG. 12 is a bottom plan view thereof.

The stippling surface shading shown throughout the drawing views represent the three-dimensional contours of the design. The broken lines shown throughout the drawing views are for environmental and illustrative purposes and form no part of the claimed design.
